Leonidas L. Badger, of Portsmouth, N. H.
Letters Patent

Mr. Schedule referred to in these Letters Patent and making part of the same containing a description in the words of the late Leonidas L. Badger himself of his improvement in the Hot air and Gasfeu Furnace.

It will be whom the yeas are to the 1st day of June
that of Leonidas L. Badger of Portsmouth in the County of Rockingham
and State of New Hampshire, has invented constructed and applied to his
a new and useful improvement called the Hot air Gasfeu Furnace, of which
the following is a full and exact description.

The furnace consists of two vertical cylinders about four feet ^{low} in
height, the bottom end of one three feet diameter. The top two feet, the
other one inch in diameter is for having a space when placed on the bottom
of about one inch. The bottom is arranged in the usual way of common
Cupola furnaces, on the top of cylinders or body of furnace is a ring pro-
jecting with a moulding running back from under the thickness of the
Brick lining to receive the two cylinders which I call the hot air cylin-
ders. These are to be arranged that the outside shall be on a line with the
furnace body, and shall be half the height of the same, one other cylinder
of the same length four inches ^{is} to be placed on a rim
on the inside leaving a chamber for the air of four inches in the clear, which
being the same as the thickness of the Brick lining, will leave the regular-
ity of the cone on the interior of the furnace equal and perfect. On the top
of these air chamber cylinders is to be a ring filled with ~~the~~ moulding, on
the interior of this air chamber is a spiral plate running entirely around
several times, leaving the distance between of about four inches making in re-
ality a circular pipe of four inches square, or it may be divided by partitions
or any other mode that will give the continuous chamber for the air, on
the back side of the cylinders at the upper end a hole is to be cast for the
Bellows pipe to be connected at the two opposite sides, on the bottom edge
two holes are left for the supply pipes which end in air tight chutes. These

the burner to the side of the furnace. The pipe at the end which on turns the effect is to be turned to get light that all variation, in the whole work, caused by contraction and expansion of the metal may be overcome. The whole may be made of cast or sheet iron, and secured together by bolts. The model I have made with the body formed of one cylinder to show more readily the mode arranging the pipes &c. on it may be used with a single cylinder. The whole furnace is to be set on a foundation in the usual way. What I claim as my invention is, the double cylinder at the top of the furnace forming a circumferential chamber for the air heating the blast from the flues of the furnace thereby causing a great saving of fuel and time. Also I claim the double cylinder to the body of furnace preventing the escape of the heat by the confined air between the two cylinders.

*L. Badger and Richard Walker of Portsmouth, N.H.
Letters Patent*

The Schedule referred to in these Letters Patent and making part of the same, containing a description in the words of the said L. V. Badger and Richard Walker themselves of their improvement on the Hot air forge, heat.

To all to whom these presents shall come,
Be it known that we Richard Walker and Leonidas V. Badger
of Portsmouth in the County of Rockingham and State of New
Hampshire have invented constructed and applied to use a new and
useful improvement called the Hot air Forge or hearth. Our invention
consists of a case or box containing under and at the side of the forge
making about one foot square for hearth and the same from front
the distance from the hearth and front to the back and bottom should
be about two and a half or three inches. The box to be closely fit-
ted with cover. The interior of box is filled with combustibles
leaving a space between ^{equally} two inches, causing the blast or wind to pass
from one continuously making a distance of eight feet in the
size box described above, the air by taking a circuitous route un-
der the hearth and in front of fire becomes intensely heated, thereby
making a great saving of fuel, the hearth should be placed
about three inches below the surface of brick work for a recepta-
cle for the fore, ashes, cinders &c.

What we claim as our improvement is, the passing the wind an-
der and back of the fire making a complete hot blast.
